DESIGN FOR A FINGER RING

Lewis Baranov, Los Angeles, Calif.

Application December 8, 1945, Serial No. 124,552

Term of patent 3½ years

(Cl. D45—10)

To all whom it may concern:

Be it known that I, Lewis Baranov, a citizen of the United States, residing at Los Angeles, in the county of Los Angeles and State of California, have invented a new, original, Design for a Finger Ring, of which the following is a specification, reference being had to the accompanying drawing, forming part thereof.

Fig. 1 is a top plan view of a finger ring showing my new design.

Fig. 2 is an elevational view of one side of the ring shank.

Fig. 3 is an elevational view of the opposite side of the ring shank from that shown in Fig. 2.

I claim:

The ornamental design for a finger ring, substantially as shown.

LEWIS BARANOV.
